UNITED STATES PATENT OFFICE

ROBERT W. ALLERTON, OF SOUTH ORANGE, NEW JERSEY, ASSIGNOR TO WORTHINGTON PUMP AND MACHINERY CORPORATION, OF NEW YORK, N. Y., A CORPORATION OF VIRGINIA

PUMP

Application filed August 12, 1924. Serial No. 731,539.

This invention relates particularly to that type of pumps used with hot liquids and is intended especially for use in oil cracking processes and the like, in which oil is handled at very high temperatures.

5 The invention includes a novel form of sealing means for the pump plunger rod, by which injury to the packing by contact therewith of the portion of the rod subjected to 10 contact with the hot oil in the pump cylinder, and danger of the hot oil flashing and causing fire, are avoided, all leakage from the pump cylinder is avoided, and oil may be supplied directly to the cylinder and used for 15 sealing, the oil thus supplied to the cylinder preferably being make-up oil for the system.

For a full understanding of the invention a detailed description of a construction embodying the invention in its preferred form 20 will now be given in connection with the accompanying drawings, and the features forming the invention then be pointed out in the claims.

In the drawings—

25 Figure 1 is a longitudinal section of a pump equipped with the invention;

Figure 2 is an end view, looking to the right on the line 2—2 of Fig. 1, and

30 Figure 3 is a central longitudinal section of the stuffing box and sealing means for the plunger rod.

Referring to the drawings:

The pump shown is of the type known as a 35 block pump formed from a single forged block of metal 20, the pump shown being a two cylinder or duplex pump, although this is not essential. The block 20 has bores forming the pump cylinder or chambers 21 in which are mounted the usual liners 31 in which move 40 the plungers 26 operated by plunger rods 27. The suction and discharge valves (not shown) are mounted in valve bores 50 cutting the cylinders 21 and the suction and discharge passages 22, 23. These valve bores are shown as 45 closed by plugs 11. The valves and their mountings may be of any suitable form.

Referring to the parts especially embodying the invention, the plunger rods 27 run through stuffing boxes 28 which are of such 50 length as to prevent the parts of the rods sub-

jected to contact with the hot oil in the pump cylinder from coming into contact with the atmosphere or with the packing, when the plungers are at the end of their strokes to the left in Fig. 1. Each box 28, starting from 55 the pump cylinder, encloses a sleeve 17 of suitable metal so formed as to provide a small clearance between it and the plunger rod, and a metal lantern gland 14 between the sleeve 17 and packing 16 of any suitable form. The chamber enclosing the rod 27 and formed by the lantern gland 14 connects with a pipe 15 through which oil is delivered under pressure to the rod chamber. The pressure of the oil supplied through pipe 15 in some cases 60 may be in excess of the highest pressure in the cylinder, but, as the pressure in these oil cracking processes is quite high, it is economical and preferable that the oil should be supplied to pipe 15 only under a pressure slightly 65 in excess of the suction pressure, so that oil will flow through the clearance between the rod 27 and the metal block 17 only during the suction stroke. With the pressure on the oil 70 supplied through pipe 15 in excess of the suction pressure but less than the discharge pressure, provision must be made for preventing the return of the oil from the cylinder through pipe 15 under discharge pressure, and for this purpose a non-return check valve on pipe 75 80 85 90 95 100 15 will be provided. As shown in Fig. 2, the pipes 15 for the two cylinders are each provided with check valves 19 and these two pipes 15 are coupled to a supply pipe on which is a hand valve 51, so that the supply of oil may be regulated as desired. The stuffing box, or that portion of the box between the packing and the cylinder, may be cooled by any suitable cooling jacket, if desired, so as to keep cold oil next the packing.

The oil supplied to the cylinders through pipes 15 may be taken from any part of the system, the oil in these cracking processes usually being circulated in a closed circuit, but preferably the oil will be taken from a source outside the circuit and in quantity such as to constitute the make-up oil, to maintain the quantity of oil desired in the system, and avoiding any other provision for adding make-up oil to the circuit. The quantity of

oil fed to the cylinder may be fixed as desired by the supply through pipe 15, the clearance of the plunger rod in the cylinder head being less or more as required. It will be understood, however, that any other provision for make-up may be used and the pipes 15 not be used for the supply of make-up. With this construction there will be no leakage of oil through the packing 16, the danger of fire due to oil leaking past the stuffing box is avoided, and the hot part of the piston rod which is in direct contact with the hot oil in the cylinder is not exposed to the atmosphere nor does it come in contact with the packing. The flow of oil to the cylinder also acts to flush any coke or other small particles back to the cylinder and thus protects the packing. The oil from the pump may be cooled, preferably by make-up oil to save the heat, and then used in the plunger-rod chamber.

It will be understood that various changes may be made in the details of construction herein shown and described, while retaining the invention defined by the claims.

What is claimed is:

1. A pump for hot liquids having a chamber enclosing the plunger rod with provision for flow of liquid from said chamber to the plunger chamber, means for supplying liquid to said rod chamber under pressure, a non-return check valve for preventing the return of the liquid from the plunger chamber, and a valve for regulating the supply to the rod chamber.
2. A pump for hot liquids having a chamber enclosing the plunger rod with provision for flow of liquid from said rod chamber to the plunger chamber, and means for supplying liquid to said rod chamber under pressure in excess of the pump suction pressure but less than the pump discharge pressure.
3. A pump for hot liquids having a chamber enclosing the plunger rod with provision for flow of liquid from said rod chamber to the plunger chamber, means for supplying liquid to said rod chamber under pressure in excess of the pump suction pressure but less than the pump discharge pressure, and a non-return check valve for preventing the return of the liquid from the plunger chamber.

In testimony whereof, I have hereunto set my hand.

ROBERT W. ALLERTON.
